J. WALDHEIM

TYPEWRITING MACHINE

Filed July 25, 1924

Patented Apr. 12, 1927.

1,624,697

UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 25, 1924. Serial No. 728,073.

This invention relates to improvements in bookkeeping devices, attachable for use upon the carriage of an Underwood standard bookkeeping machine. In such machines entries are made on individual cards or memorandum-sheets, and copies of such entries are also kept or made upon proof or record sheets, as usual. A single entry is made at any particular time upon each memorandum-sheet, while the proof or record-sheet is retained in the machine and thereafter all the entries are made thereon in sequence until the sheet is full.

One of the objects of the present invention is to provide a simple, efficient and inexpensive attachment for the type of the aforementioned machine which will effectively position relatively to the rotatable platen of the machine, and longitudinally thereof, a typewriter-ribbon which is auxiliary to the usual and main typewriter-ribbon found in such machine, and in such a manner that the auxiliary-ribbon is suitably divided into two stretches, one of which is positionably adjacent the printing line of the machine, and the other of which is arranged out of longitudinal alignment so as to be spaced vertically from the other stretch and from said printing line.

This expedient finds particular application in all cases where it is desirable to maintain in proper feeding relation, upon the platen of a typewriting machine, a plurality of sheets, say two sheets, one overlapping the other and being of a greater width in conjunction therewith, so as to leave a margin upon the wider sheet. This arrangement of sheets is serviceable to allow inscriptions to be typed, line by line, upon the relatively narrower sheet, so as to assure, through the medium of carbon-sheets, or the like, that those same impressions be produced simultaneously upon the wider sheet; and without shifting one sheet with respect to the other sheet, and while the platen and carriage continue to make their rectilinear traverse, it is possible to type inscriptions upon the margin of the wider sheet which flanks the narrower sheet, so that these inscriptions may be in line with the line of inscriptions already typed upon the narrower sheet, while the carriage and platen are finishing the same traverse across the machine.

The present invention interleaves between

the two sheets, not carbon-sheets, but a typewriter-ribbon which extends completely across the longitudinal axis of the platen, projecting beyond the effective width of the narrower sheet and extending completely across the margin of the wider sheet by reason of the manner in which the two stretches of this typewriter-ribbon, already explained, are arranged in vertically spaced-apart relation. It will readily be seen that one of these stretches is allotted to the narrower sheet extending completely across the same, and the other stretch of the same ribbon is allotted exclusively to the marginal portion of the wider sheet, so as to allow the first stretch to be located at the printing line of the machine and the other stretch in a position spaced away therefrom, thereby exposing to view of the typist any inscriptions that may have been typed upon the marginal portion of the wider sheet which are located also at the printing line of the machine. It will be understood that the main typewriter-ribbon is arranged so as to always come into printing-line position, so that upon the impinging of the usual type-bar therewith at all points upon its surface co-extensively with the full length of the platen impressions are made at the printing line across the narrower sheet, which are reproduced, owing to the impinging of the same type-bars with the auxiliary ribbon, upon the wider sheet, and impressions are also produced, directly, through the main ribbon, upon the marginal portion of the wider sheet at the printing line (as contradistinguished from being reproduced), because in this region the main ribbon does not overlie and is not in longitudinal alignment with the auxiliary ribbon. In other instances the applications of the present invention may be multiplied with like results.

Another object of the present invention is to provide suitable means for feeding the auxiliary typewriter-ribbon relatively to the platen, so as to advance intermittently fresh surfaces of this ribbon that may be impinged upon by the typing mechanism of the machine. In carrying out this result the auxiliary typewriter-ribbon is located upon the paper-carriage so as to travel with the same, and take-up mechanism is arranged also upon the carriage and may be controlled, in operation, by the line-spacing

mechanism for urging the auxiliary ribbon along in movable relation with respect to the fixed point of engagement of each type-bar relatively to the traveling platen. By means of the present invention any portion of the length of the auxiliary ribbon may be instantly offset with relation to another portion within the zone of the printing operation, so that, while one portion extends along the printing line, the other portion is spaced therebeyond; likewise it is possible to dispose and position a given length of the auxiliary ribbon so that it extends completely across the length of the platen, and is located at the printing line or beyond the printing line, as exigencies may dictate, and when it is desired to shift, insert or remove either or both of the sheets held against the platen of the machine, the present invention is arranged to be manually lifted with its auxiliary ribbon out of contact with the sheets, so as to permit this action to take place conveniently.

Other features and advantages will hereinafter appear.

In the accompanying drawings,

Figure 1 is a front elevation of the invention, showing certain parts partly broken away.

Figure 2 is a front elevation of the present invention, showing a shifted sheet located on the platen.

Figure 3 is a transverse sectional view of the invention, showing the details of construction of the ribbon-feeding means.

Figure 4 is a top plan view of Figure 3.

Figure 5 is a section taken transversely through the movable ribbon-guide forming part of the present invention.

Figure 6 is a diagrammatic view of the present invention, showing the auxiliary ribbon disposed exactly at the printing line of the machine.

Referring to the drawings which are merely illustrative of the present invention, 10 and 11 designate the side members or pieces of the usual platen-frame in which is journaled the platen-shaft 13 carrying the platen 12 which may be rotated by the usual hand-wheel 14 or other means associated with the line-spacing or ratchet-wheel 15.

The present invention includes a suitable frame arranged to be supported so as to be movable upon the ends of the carriage-frame 55 by means of bracket-plates 17 and 18 which overlie the side pieces 10 and 11 of the platen-frame alongside of the usual end plates 16 of said frame. Said bracket-plates have depending side supports or webs 19 and 20, and are also formed at one end with integral lugs 21, which are suitably pivoted on pins 22 carried by ears 23 having flanges 24 secured by fasteners 25 upon the side pieces 10 and 11 of the platen-frame. The paper-shelf, incidental to typewriting machines, is

designated 26, and has its lower end curved at 27 concentrically with the lower plane of the platen 12.

There is also shown the usual main typewriter-ribbon 28 which is vibrantly supported so as to be located at the printing line of the machine whenever a typing action is about to take place, by means of type-bars 29 carrying the type-surfaces 30.

The bracket-plates 17 and 18 are formed intermediate their ends with hanging lugs 31 in which are trunnioned the pintles 32 of spools 33 having guide-flanges 34 and associated in movement operatively with a ratchet-wheel 35. The rotation of the spools, or either of them, takes place against the tension of pressure plates 36 which are shown in the shape of spring arms 37 pressed yieldingly against the spools by means of adjustable tensioning thumb-screws 38.

The auxiliary typewriter-ribbon 39 is shown extending across the length of the platen and beyond the ends thereof, being operatively supported and fed along in zig-zag manner relatively to the platen by means now to be described.

The spools 33 are located in a plane at right angles to the longitudinal axis of the platen, and in the course of feeding the opposing ends of the auxiliary ribbon off from or onto the spools, it becomes necessary to divert and change the direction of movement of this auxiliary ribbon, so that the intermediate portion thereof may be disposed at right angles with respect to the direction of said spools, and thus occupy a position alongside of the main ribbon 28, as shown in the drawings, but inasmuch as the intermediate portion of this ribbon has to be offset to position one stretch thereof in elevated relation with respect to the other stretch thereof, it becomes necessary to change the direction of movement of the intermediate portion of this auxiliary ribbon at another point, between the ends of the platen, at which point the ribbon takes a vertical direction of movement with respect to the aforementioned stretch, so that the moment any point of the auxiliary ribbon 39 leaves either of the spools 33 in its course of movement towards and upon the other spool, it changes its direction thrice, and in each instance it has impressed thereon a diagonal turn, these diagonal turns being designated respectively 39^a, 39^b and 39^c to differentiate them.

40 designates an ear turned up upon each of the webs 19 and 20 of the bracket-plates 17 and 18, upon which are trunnioned rollers or idlers 41, over which passes the auxiliary ribbon directly from the spools 33, and is led therebeyond so as to be turned over another roller 42, trunnioned upon an ear 43, also struck up from the web 19 or 20. Brackets 44 are secured by suitable fasteners 45 upon the webs 19 and 20 immediately above the

5 idlers 41 and hold supportingly in position the reduced ends 47 of a bar 46 which is thus positioned so as to extend completely across the length of the platen at the upper plane thereof. Fixed ribbon-guides are provided 10 in the shape of plates 50 and 52 which are disposed substantially perpendicularly with respect to the bracket-plates 17 and 18, so as to be located and extended across, below and in front of said spools, as shown particularly in Figures 1 and 2. The guide-plate 50 is made longer than the guide-plate 52, so as to extend further down below the latter and both are formed with oppositely-inclining 15 diagonal slots 51 and 53, respectively, one being spaced below the other; the slot 51 of plate 50 extending down below the slot 53 of the plate 52. The auxiliary ribbon 39, after leaving the idlers or rollers 42, passes 20 downwardly into the diagonal slots 51 and 53, undergoing a change in direction diagonally, as at the portions indicated 39^a, 39^c, respectively, so that they are permitted to assume a distinctly horizontal direction of 25 movement which causes the intermediate portion of this ribbon to move longitudinally and horizontally across the platen.

30 The movable ribbon-guide has its upper portion arranged preferably in the shape of a sleeve 54, slidably engaging a rail or track 48 secured by fasteners 49 longitudinally of the back of the bar 46 in spaced relation thereto. Depending from the sleeve 54 is a plate 55 extending downwardly to the 35 lowermost point of the plate 50 and formed with a pair of vertically-separated diagonal slots 57 and 58 which extend in the same direction, so that the upper slot 57 extends in the same direction and in horizontal alignment 40 with the slot 53, formed in the plate 52, and so that the lower diagonal slot 58 extends in the opposite direction with respect to and in horizontal alignment with the diagonal slot 51 formed in the plate 50. The intermediate portion of the auxiliary 45 ribbon 39, at the points where it leaves the slots 51 and 53 in the plates 50 and 52, extends across the platen, entering one of the diagonal slots 57 or 58, say slot 57, and movably projecting therethrough so as to be 50 movable along the front surface of the guide-plate 55. The ribbon 39 is also arranged to movably project through the other slot 58, so that this stretch 39^b is disposed diagonally 55 with respect to the longitudinal axis of the platen, and moves in a vertical direction at this point, and so that at one side of the plate 55 the stretch 39' is disposed horizontally, and at the other side thereof the stretch 39'' also extends horizontally, but is vertically spaced with respect to the stretch 39'.

60 A handle 59 is secured upon the bar 46 by means of which this bar and the pivotal frame carrying it may be lifted and swung

upon the pivots 22, so that the auxiliary ribbon 39 may be moved out of contact with the platen 12, and thus provide clearance for enabling either or both of the sheets A and B to be relatively shifted adjacent the platen or otherwise manipulated relatively thereto. 65 designates a stop secured upon the outer face of the bar 46 and spaced inwardly from the adjacent end of the platen, this stop having a side gage 61 allowing one edge 70 of the memorandum-sheet B to engage it so as to properly space this sheet with respect to the relatively wider record-sheet A.

75 As an effective means for feeding along the superposed stretches of the auxiliary ribbon 39 so as to progressively present a fresh surface of said ribbon against the action of the type-bars 29, mechanism is provided preferably controlled by the line-spacing mechanism of the machine for intermittently 80 unwinding the ribbon off one of the spools and winding it up onto the other spool. Suitably secured upon the line-space slide 62 is a bracket-plate 63 secured thereto by means of a fastener 64, which plate 63 has 85 an angular arm 65 which has a lug 66, receiving the pivot-pin 68 upon which is fulcrumed the pawl 67 having ratchet-engaging point 69, this pawl being held yieldably in a horizontal position by means of a spring 70 90 which is secured fixedly upon a stud 71.

95 From the foregoing description, it will be seen that the movable ribbon-guide-plate 55 is designed so as to slide upon the rail 48 lengthwise of the platen, so as to be held stationary at any point relatively thereto by means of the thumb-screw 56. As this plate 55 moves it always maintains two stretches of the ribbon 39 at opposite sides thereof in 100 perfect horizontal alignment, the distance it has been adjusted with respect to either end of the platen determining the variable length of one of the stretches with respect to the other stretch spaced vertically therefrom, so that this guide-plate 55 can be fixedly 105 mounted at one extreme end of the platen, as shown in Figure 2, so as to position the stretch 39'' thereof above the printing line, which latter is illustrated by the inscription "Dear sir" indicated at I, or this guide-plate 110 may be held stationary at the other extreme end of the platen, shown diagrammatically at Figure 6, whereby the stretch 39' of the auxiliary ribbon will be held exactly at the printing line of the machine, allowing two 115 sheets of comparatively equal width to receive simultaneously typed impressions, the outer sheet being typed through the instrumentality of the main ribbon 28, and the other sheet being typed through the instrumentality of the auxiliary ribbon 39 interleaved between the two sheets. It will be 120 seen that when the machine is to be used for another kind of work in which the auxiliary ribbon is not required, said ribbon may 125 130

be temporarily rendered ineffective, as illustrated in Figure 2, where the ribbon-guide has been moved to the extreme left-hand side or end of the platen, out of printing-line position, thus exposing the printing line of the work-sheet, where the latter may have been typed upon through the medium of the main ribbon.

To avoid smudging of the work-sheet which may be inserted into the machine prior to shifting the ribbon-guide, said ribbon is threaded with its two horizontal stretches 39' and 39" in a manner to be positioned relatively to, so as to be located behind, the guide. The vertical stretch 39^b which joins the two horizontal stretches 39' and 39", and which have a relative motion, extends in front of the guide, thus avoiding the rubbing action of the ribbon against the work-sheet.

The present invention finds immediate application in the typing of monthly statements concerning which a record copy is made of the same entries on a memorandum-sheet inserted in the platen, such entries being made on the same date in the various statements. Such a type of machine is described in Smith Patent No. 1,377,446, dated May 10, 1921, in which form of invention the ribbon-guide may be permanently set in definite position.

After the record-sheet A and memorandum-sheet B are inserted in the position shown in Figure 1, with one edge of the memorandum-sheet B engaging the side gage 61, and with its other end spaced forwardly from the adjacent edge of the sheet A, whereby the marginal portion of sheet A is visible, the following typing action may take place in the preparation of monthly statements. When the sheet A has its outer edge A' disposed at the printing line the marginal portion thereof, which flanks the sheet B, is typed, through the instrumentality of the main ribbon 28, with the name of a firm, say "James Smith," as indicated at G. Previously thereto the ribbon-guide 55 is positioned so as to overlap the edge B' of sheet B, so that the stretch 39' extends completely across the width of sheet B at printing-line position, while the stretch 39" is held above stretch 39', so as to expose the margin of sheet A at the printing line, in which last-named zone the inscription "James Smith" is printed. The two sheets A and B are then successively line-spaced, line by line, and when the upper edge B' of the sheet B is in printing-line position the inscription or name of the firm "John Doe" is typed, as indicated at C, at which time the type-bars 29, when the platen is brought to the proper point opposite the margin of sheet A, effect the typing, through the medium of the main ribbon 28, the same name "John Doe" upon the marginal portion of

sheet A, as indicated at H, both inscriptions C and H being, at this time, in horizontal alignment and located at the printing line of the machine. Any number of account entries may be typed along the same line between inscriptions C and H against the main ribbon 28, so as to produce impressions of these entries upon sheet B, and reproduce the same impressions through the medium or stretch 39' of ribbon 39 upon the record-sheet A, such additional entries being designated broadly "F." Similarly the two sheets are moved or spaced the next line on the platen 12, and now a date, such as is indicated at D in one line and E in another line, is typed upon both sheets through the medium of both ribbons together with inscriptions of entries "F." By means of this arrangement, while the record-sheet A is held stationary against the platen, the memorandum-sheet B may be moved line by line, relatively thereto, as may be necessary, so that any particular date and account entries may be typed simultaneously upon the two sheets at any point thereof along the printing line of the machine opposite the name of the firm H, exposing to the view of the typist the margin of the sheet A held stationary against the platen.

It may be desirable to provide a lever or levers 72, fulcrumed upon a stud 73, and carrying a roller or rollers 74 which engage the sheets A and B under tension at the upper plane of the platen, so as to press these sheets against the latter, a suitable spring or springs 75 applying the tension against the rollers. By means of this engagement of these rollers, the sheet A is held stationary and against slipping in the paper-shelf 26 by means of the tension rollers 74 when the front and rear pressure rollers 76 and 77 are released from contact with the under side of the platen, while the sheet B, released by said rollers 76 and 77, is removed from the machine; it is also possible, in this manner, to insert the sheet B without moving sheet A, although rollers 76 and 77 are disengaged from the platen. After both sheets are properly mounted in position the proper rollers 76 and 77 re-engage with the platen to hold these sheets in the usual manner, and then the roller 74 may be disengaged in any suitable manner (not shown). Since the ribbon-guide-plate 55 is disposed intermediate the ends of the auxiliary ribbon, said guide-plate serves as a means to prevent the ribbon from being dragged around the platen with the work-sheets when the platen is reversely rotated.

Variations may be resorted to within the scope of the invention, and portions of the improvements may be used without others.

Having thus described my invention, I claim:

1. In a typewriting machine, the combina-

130

tion with a platen and a ribbon-vibrator adjacent the printing line of said platen, of means for supporting a length of auxiliary typewriter ribbon lengthwise of said platen at said printing line, and a shifter arranged for permanently shifting selectively part or all of said length of auxiliary ribbon edge-wise out of and into typing position.

2. In a typewriting machine, the combination of a carriage, a platen-frame, a platen revolvably mounted in said frame, a main typewriter-ribbon vibrantly mounted alongside said platen, and an auxiliary typewriter-ribbon extending lengthwise adjacent said platen and having means whereby it is divided into two stretches, one maintained at the printing line of the platen and the other spaced away from said printing line.

3. In a typewriting machine, the combination of a platen-frame, a carriage upon which said frame is mounted, a platen revolvably mounted in said frame, a main typewriter-ribbon relatively to which said carriage moves, an auxiliary typewriter-ribbon moving with said carriage, and means manually operable and designed to move any portion of the length of said auxiliary ribbon into or out of printing-line position relatively to the position of the main ribbon.

4. In a typewriting machine, the combination with a platen and a ribbon vibrator adjacent the printing line of said platen, of means for supporting a length of auxiliary typewriter ribbon lengthwise of said platen behind said vibrator at said printing line, and a shifter plate provided with two diagonal slots and movable along said platen, said ribbon passing through said slots, so that part or all of said length of auxiliary ribbon may be shifted edge-wise out of and into typing position.

5. In a typewriting machine, the combination with a carriage, a platen, and a ribbon-vibrator adjacent the printing line of said platen, of two slotted guides for supporting a length of auxiliary typewriter ribbon lengthwise of said platen behind said vibrator, a track parallel with said platen and supported on said carriage, and a shifter plate mounted for lateral movement on said track and provided with two diagonal slots one above the other, said auxiliary ribbon being arranged to engage in said diagonal slots whereby the movement of said shifter plate on said track in one direction will shift part or all of said length of ribbon edge-wise above typing position, and movement in the opposite direction will return part or all of said ribbon to typing position.

6. In a typewriting machine, the combination of a paper-carriage, a revolvable platen operatively connected thereto, so as to move therewith, a main typewriter-ribbon extending longitudinally of the platen, an auxil-

70
iary typewriter-ribbon on said carriage and normally held between the main ribbon and said platen, ribbon-guides at different elevations at the ends of the carriage, and means adjustable longitudinally of said platen and engaging the auxiliary ribbon for shifting a portion thereof into and out of alignment with the lower of said end guides and thereby bringing said portion into and out of printing-line position relatively to said 75 platen.

7. In a typewriting machine, the combination of a frame, a carriage moving relatively to said frame, a main typewriter-ribbon operatively movable in fixed position and supported upon said frame, a platen rotatably mounted relatively to said carriage, an auxiliary typewriter-ribbon supported upon said carriage and extending longitudinally of said platen, and means mounted upon 80 said carriage and moving lengthwise of said auxiliary ribbon for interchangeably holding at the printing line of the platen the entire stretch of said auxiliary ribbon or any portion thereof.

8. In a typewriting machine, the combination with a carriage, a platen on said carriage, and a line-shifting mechanism for said platen, of a typewriter ribbon extending lengthwise of said platen forward of 90 the same, means for offsetting part of said ribbon so as to dispose one stretch of the ribbon at the printing line of said platen and another stretch above said printing line and parallel to the first stretch, and instrumentalities arranged for intermittently advancing said ribbon upon operation of said line-shifting mechanism.

9. In a typewriting machine, the combination of a platen-frame, a platen revolvably mounted therein, a main typewriter-ribbon fixed in position and disposed at the printing line of the machine, means for causing said platen to move rectilinearly relatively to and adjacent said main typewriter-ribbon, an auxiliary typewriter-ribbon, means for supporting the auxiliary ribbon relatively to said platen, so as to move therewith, and a manually-controlled means engaging said auxiliary ribbon between its ends for 105 offsetting one stretch thereof relatively to another, so as to cause either stretch to be disposed at printing-line position opposite the main ribbon and the other stretch spaced out of printing-line position at the same 110 time.

10. In a typewriting machine, the combination of a platen-frame, a platen revolvably mounted therein and movable rectilinearly, a main typewriter-ribbon held fixedly at 125 printing-line position adjacent said platen, a swinging frame having supports positioned at the ends of said platen, an auxiliary typewriter-ribbon operably mounted upon said swinging frame, so as to extend 130

lengthwise of said platen in back of the main ribbon, and means moving relatively to said swinging frame for offsetting the auxiliary ribbon to cause only one stretch thereof to be disposed at printing-line position, thereby exposing part of the platen in the printing-line zone.

11. In a typewriting machine, the combination with a carriage and a platen, of an upwardly swinging frame pivotally mounted on the ends of said carriage and having a member parallel with said platen, a length of typewriter ribbon having its ends supported on the ends of said frame and extending therefrom lengthwise of said platen, and a movable shifter mounted on said frame member and arranged for supporting said ribbon intermediate its ends, said shifter having two diagonal slots engaging around said ribbon whereby the movement of said shifter will offset said length of ribbon into two parallel stretches, one of which is positionable at the printing line of said platen and the other above said printing line.

12. In a typewriting machine, the combination of a paper-carriage, means for moving the same rectilinearly, a revoluble platen operably associated in movement with said carriage, a typewriter-ribbon extending longitudinally adjacent said platen, a pair of spools rotatably mounted at the ends of said carriage, upon which the ends of said ribbon are operably and interchangeably engaged so as to be advanced longitudinally, swinging supports carrying said spools and causing said ribbon to move away from said platen when they are swung upon said carriage, means movable lengthwise of said platen for supporting said ribbon between its ends, means for guiding the last-named means in movement, and means whereby said ribbon may be threaded upon the last-named supporting means therefor in a manner to be offset vertically, so that one of said stretches may be disposed in printing-line position and the other stretch may be spaced therefrom and be free from contact with the type mechanism of the machine.

13. In a typewriting machine, the combination of a slidable paper-carriage, a platen revolvably mounted therein and movable therewith, spools rotatably mounted upon said carriage, a typewriter-ribbon having its opposite ends wound upon said spools, means for supporting said ribbon in a horizontal plane adjacent said platen with one stretch spaced vertically from another stretch thereof, and means for feeding along the mentioned stretches of said ribbon on and off said spools.

14. In a typewriting machine, the combination with a carriage, a platen, types for printing against said platen, a lever for line-spacing said platen, and a main typewriter

ribbon arranged for engagement by said types at the printing position on said platen, of a length of auxiliary typewriter ribbon extending lengthwise of said platen and positioned in back of said main ribbon, means operable by said line-spacing lever for feeding said auxiliary ribbon relatively to said platen, a track on said carriage parallel with said platen, and a ribbon guide laterally movable on said track and arranged to shift a part or all of said length of auxiliary ribbon into and out of engagement with said types.

15. In a typewriting machine, the combination of a movable carriage, a platen rotatably mounted therein, a pair of ribbon-guides supported at the ends of said carriage, spools positioned in proximity to said ribbon-guides, a typewriter-ribbon wound upon both of said spools and movably supported in said guides, so as to present a longitudinal stretch adjacent said platen, and a movable ribbon-guide engaging the mentioned stretch of said ribbon to offset the same in a vertical plane whereby one portion of said ribbon is mounted at the printing line of the machine and the other portion is held spaced from said printing line.

16. In a typewriting machine, the combination of a movable paper-carriage, spools rotatably mounted upon the ends of said carriage, stationary ribbon-guides supported in a plane with said spools, a movable ribbon-guide playing between said stationary ribbon-guides, means carried by said carriage for guiding said movable ribbon-guide, a typewriter-ribbon wound upon said spools passing movably through said stationary ribbon-guides and movably passing through the movable ribbon-guide, means for fixing said movable guide in position between the spools, and means carried by said movable ribbon-guide for causing a portion of said ribbon extending between said spools to be maintained at the printing line of the machine.

17. In a typewriting machine, the combination of a movable paper-carriage, platen-frame members disposed at the ends of said carriage, a platen rotatably mounted with respect to said members, a pair of supports pivotally mounted upon said frame members, a track extending longitudinally of and beyond said platen and having its opposing ends secured upon said pivotal supports, a typewriter-ribbon, means stationed upon said pivotal supports for winding on and off, respectively, the opposite ends of said ribbon, so as to feed said ribbon relatively to said platen, means disposed in a plane with said first-named means for disposing said ribbon in horizontal position adjacent said platen, and means slidably engaging said track and connected to said ribbon for offsetting the latter and producing two

stretches upon said ribbon spaced apart vertically.

18. In a typewriting machine, the combination of a slidable paper-carriage, a platen 5 rotatably mounted thereon, platen-frame members disposed at the ends of said carriage, a pair of supports pivotally mounted upon said platen-frame members, a bar extending supportedly from said pivotal supports longitudinally in front of said platen, 10 a typewriter-ribbon, means stationed at the ends of said bar and engaging said ribbon to hold the same stretched out longitudinally adjacent said platen, means on said supports 15 for feeding said ribbon along at one end of said platen, a ribbon-guide slidably disposed relatively to said bar and allowing said ribbon to pass therethrough in offset formation, and means for locking said ribbon-guide in adjusted position fixedly with respect to the offset portions of said ribbon. 20

19. In a typewriting machine, the combination of a paper-carriage moving rectilinearly, a platen rotatably mounted in operative relation with said carriage, platen-frame members positioned at the ends of said carriage, a bar extending longitudinally of and beyond the ends of said platen, side bars carrying the ends of said bar and being 25 movably secured so as to be supported upon the platen-frame members, but permitting said bar to be lifted relatively to said members, manually-controlled means mounted upon said side bars and engaging the opposite ends of a typewriter-ribbon to feed the same along relatively to said platen, a track mounted upon said bar, a ribbon-guide slidably engaging said track, means for locking said ribbon-guide in adjusted position upon 30 said track, and means carried by said guide and movably receiving said ribbon, so as to offset the same with one stretch thereof spaced vertically with respect to the other stretch thereof. 35

45 20. In a typewriting machine, the combination of a slidable paper-carriage, a platen rotatably mounted relatively thereto and moving therewith, a typewriter-ribbon, means carried by the ends of said carriage 50 for movably engaging the ends of said ribbon to stretch the same longitudinally across said platen and beyond the ends thereof, said ribbon being intermittently fed along relatively to said platen, a ribbon-guide normally positioned at one end of said platen, a paper-stop operatively mounted upon said carriage in advance of the normal position of said ribbon-guide, said ribbon being held by said ribbon-guide normally at the printing line 55 of the machine, and means for manually moving said ribbon-guide lengthwise of said platen, said movable ribbon-guide being arranged for pushing said ribbon away and out of printing-line position. 60

65 21. In a typewriting machine, the combination of a slidable paper-carriage, platen-frame members, a rotatable platen having its ends mounted in said members and movable with said carriage, a bar extending longitudinally of said platen with its ends projecting therebeyond, side bars secured to the ends of said bar and pivotally mounted upon said members and depending therefrom, a typewriter-ribbon arranged to extend longitudinally adjacent said platen, means mounted upon said side bars for feedingly supporting and guiding the end portions of said ribbon, a track carried by said bar, means suspended movably upon said track and engaging said ribbon to offset the same into two horizontal stretches spaced apart in a vertical plane between the ends of said platen, and a handle carried by said bar by which it and said ribbon may be lifted out of operative position, through said side bars, adjacent said platen. 70

75 22. In a device of the kind described, the combination of a longitudinally-extending bar, side bars extending at right angles to and supporting the ends of said bar, means for attaching said side bars upon a platen-frame, a pair of spools operatively journaled under tension upon said side bars, a ribbon-guide supported upon each of said side bars below said spools, each of said guides having oppositely-inclined slots disposed diagonally of the longitudinal axis of said bar, a typewriter-ribbon wound upon said spools and movably extending through said diagonal slots so as to provide a stretch extending horizontally of said bar, a track fast on said bar and parallel thereto, and means movably engaging said track and said ribbon between said spools for offsetting said ribbon to convert the latter into two horizontal stretches spaced apart in a vertical plane. 80

85 23. In a device of the kind described, the combination of a frame consisting of a longitudinal bar and substantially right-angular side bars, said side bars constructed to be pivotally secured upon a typewriter-carriage, a typewriter-ribbon, means mounted upon said side bars for feedingly stretching the ends of said ribbon, so that the intermediate portion of the latter may extend substantially parallel with said bar, a track secured in back of said bar longitudinally thereof, a ribbon-guide consisting of a portion slidably engaging said track and having a depending portion formed with a pair of vertically-spaced-apart diagonal slots extending in the same direction, through which slots the mentioned parallel stretch of said ribbon may movably pass, a handle upon said bar, and means carried by said ribbon-guide and engaging said track to lock said ribbon-guide in fixed position thereupon. 90

100 24. In a typewriting machine, the combination of a carriage, a platen-frame, a typewriter-ribbon mounted to travel with the 105

carriage, means for feeding the ribbon, a platen revolvably mounted in said platen-frame, means on said carriage for supporting the intermediate portion of said ribbon in horizontal position adjacent said platen, including ribbon-guides at different elevations at the ends of the carriage, and a shifter on said carriage adjustable longitudinally of said ribbon to offset a portion of the ribbon vertically so that one portion thereof is maintained in typing-position out of longitudinal alignment with the offset portion thereof, said end guides holding the ribbon at different elevations at the ends of the carriage, and the ribbon threaded through said shifter to change the position of the ribbon.

25. In a typewriting machine, the combination of a platen movable rectilinearly, a main typewriter-ribbon vibrantly positioned at the printing line of the machine adjacent said platen, a support spaced fixedly adjacent the upper plane of said platen, a stop mounted upon said support for spacing a sheet in advance of one end of said platen, an auxiliary ribbon extending longitudinally of said platen and having one end protruding beyond said stop, means positioned adjacent the last-mentioned end of said platen for movably supporting the protruding end of said auxiliary ribbon in a horizontal plane alongside said platen in back of said main ribbon, means for permanently maintaining the intermediate portion of said auxiliary ribbon which extends longitudinally of said platen out of longitudinal alignment with the horizontally-supported protruding portion thereof, so as to be spaced vertically therefrom, and means for variably altering the lengths of the vertically-spaced apart portions of said ribbon disposed between the ends of said platen.

26. A device of the kind described, consisting of a frame composed of a longitudinal rail, side supports arranged at the opposing ends of said rail, ribbon-guides consisting of a pair of plates fixedly secured upon said side supports, one of said plates being of a greater length than the other and projecting therebelow, each of said plates being formed with diagonal slots inclining in opposite directions, a movable guide-plate having a slidable connection upon said rail and formed with two spaced-apart diagonal slots inclining in the same direction, one of said last-named diagonal slots inclining in the same direction and in horizontal alignment with the slot in the shorter plate, and the other slot in the movable guide-plate inclining in an opposite direction with respect to and arranged in horizontal alignment with the slot of the relatively longer plate, a typewriter-ribbon movably projecting through the slot in the shorter plate and through the slot in the movable plate aligning therewith, so as to produce a horizontal

stretch spanning these two plates, said ribbon also passing through the remaining slot in the movable plate and through the slot in the longer plate, so as to produce another stretch spanning the longer plate and movable plate and arranged parallel and out of longitudinal alignment with the other stretch, and means engaging the free ends of said ribbon for successively feeding along and taking up said ends so that said stretches may be advanced intermittently.

27. A device of the kind described, consisting of a longitudinal bar, brackets upon which the ends of said bar are mounted, a rail spaced longitudinally alongside of and supported upon said bar, spools trunnioned upon said brackets in a plane at right angles to said bar, guide-plates disposed below and in advance of the ends of said bar and supported upon said brackets, idlers mounted upon said brackets between said spools and plates, one of said plates projecting below the other plate and both plates having oppositely-arranged diagonal slots, a typewriter-ribbon having its ends wound upon said spools engaging said idlers and movably protruding through said diagonal slots, means exerting tension against the rotative action of said spools, a ribbon-guide adjustably mounted upon said rail and depending below said bar, and means carried by the adjustable ribbon-guide and movably guiding the intermediate portion of said ribbon so as to divide said ribbon into two horizontal stretches, one of which is movably held at the level of the slot in the shorter plate, and the other of which is movably held at the level of the slot in the longer plate.

28. In a typewriting machine, the combination of a carriage, a platen on said carriage, a ribbon on said carriage extending lengthwise of the platen, and a ribbon-guide on said carriage to cause part of the ribbon to extend along the printing line and part to one side of the printing line.

29. In a typewriting machine, the combination of a carriage, a platen on said carriage, a ribbon on said carriage extending lengthwise of the platen, a ribbon-guide on said carriage to cause part of the ribbon to extend along the printing line and part to one side of the printing line, and in zigzag formation, and means to change the position of the zigzag of the ribbon with relation to the platen.

30. In a typewriting machine, the combination of a carriage, a shiftable device on said carriage, a platen on said carriage, a portion of ribbon extending from one side of said device along said platen to cover the printing line, a portion of ribbon extending from the other side of said device to one side of the printing line, and means to change the position of said device to increase

- the length of one portion of ribbon while the other portion of ribbon is being decreased.
31. In a typewriting machine, the combination of a carriage, a platen in said carriage, a ribbon on said carriage extending lengthwise of the platen, and a ribbon-guide to cause part of the ribbon to extend along the printing line and part to one side of the printing line.
- 10 32. In a typewriting machine, the combination of a carriage, a platen in said carriage, a ribbon on said carriage extending lengthwise of the platen, a ribbon-guide to cause part of the ribbon to extend along the printing line and part to one side of the printing line, and means to change the position of the guide to alter the arrangement of the ribbon with respect to the printing line.

33. In a typewriting machine, the combination with a carriage and a platen, of a typewriter ribbon extending lengthwise of said platen in front of the same, a guide for said ribbon at each end of said platen, the left-hand one of said guides being positioned at the printing line of said platen, and the other of said guides being positioned above said printing line, and a shifter plate movable along said platen and engaging said ribbon to cause the stretch of the latter between said left-hand guide and said movable plate to be disposed at the printing line, said plate being also arranged to cause the remaining portion of said ribbon to be disposed above said printing line and parallel thereto.

JOHN WALDHEIM.
